[57] CLAIM

The ornamental design for a keyboard stand, as shown and described.

DESCRIPTION

FIG. 1 is a perspective view of a keyboard stand in an erected state according to the inventive design;

FIG. 2 is a perspective view of a keyboard stand in a collapsed state according to the inventive design;

FIG. 3 is a perspective view of a keyboard stand according to the inventive design showing a keypad mounted thereon in phantom view;

FIG. 4 is a top plan view of a keyboard stand according to the inventive design;

FIG. 5 is a front elevational view of a keyboard stand according to the inventive design;

FIG. 6 is a right side elevational view of a keyboard stand according to the inventive design;

FIG. 7 is a back elevational view of a keyboard stand according to the inventive design;

FIG. 8 is a left side elevational view of a keyboard stand according to the inventive design; and,

FIG. 9 is a bottom plan view of a keyboard stand according to the inventive design.

The broken line showing of a keyboard in FIG. 3 is for illustrative purposes only and forms no part of the claimed design.
